UNITED STATES PATENT OFFICE.

JOE LIDDELL, OF NEW ALBANY, MISSISSIPPI.

SAFETY APPLIANCE FOR AIR BRAKES.

Application filed July 3, 1924. Serial No. 724,154.

To all whom it may concern:

Be it known that I, JOE LIDDELL, a citizen of the United States, residing at New Albany, in the county of Union and State 5 of Mississippi, have invented certain new and useful Improvements in Safety Appliances for Air Brakes, of which the following is a specification.

My invention relates to a safety appliance 10 adapted to be attached to air brakes on railroad cars for the purpose of automatically stopping a train whenever a brake beam falls down.

It is a well known fact that a great number 15 of railroad accidents are caused by defective brakes, such accidents amounting to as much as sixty percent of the total number of all accidents and it is accordingly very important for the railroads, as 20 well as the traveling public, that the causes of accidents be removed as much as possible.

In the accompanying drawings, one embodiment of the invention is illustrated, and—

25 Figure 1 is a fragmentary assembled view of the device as connected to the air brake valve;

Figure 2 is an axial section through the valve cage and adjacent parts;

30 Figure 3 is a section along line 3—3 of Figure 1;

Figure 4 is a section along line 4—4 of Figure 1,

35 Figure 5 is a section along line 5—5 of Figure 1, and

Fig. 6 is a fragmentary side elevation of a car with the safety device installed.

In the drawings, reference numeral 10 40 represents a valve cage which is of the usual construction and inserted in the pipe line 11. The cage has a main chamber 12 and a relief chamber 13 divided by a partition 14. In this partition is provided an aperture 15 forming a seat for a valve 16 45 adapted to close by gravity and mounted on a valve stem 17 guided in a boss 18 at one end and in a closing plug 19 at the other end. From the relief chamber 13 a small vent 20 opens into the atmosphere for the 50 escape of air from the valve cage.

The boss 18 has a downward extension 21 forming a guide for a toe 22 on an operating lever or trigger 23. The toe 22 is 55 pressed downwardly by a compression spring 39 abutting at its upper end against the outer wall of the cage and at its lower

end against the top face of the said toe. The latter rests, actuated by the spring, on a stop 41 at the bottom of the guide 21. The said guide forms a protective housing 60 both for the lower end of the stem 17 and for the toe 22. The lower end of the valve stem 17 extends into the recess 24 in said guide in close proximity to the toe 22 but normally free from the same. 65

The trigger 23 is fulcrumed, as at 25, on a journal 26 carried in bearings 27 forming part of the valve cage 10 and a long arm 28 of the trigger terminates with an eye 29 from which a rod 30 is suspended upon a 70 pivot pin 31. The rod 30 is provided with a plurality of apertures 32 with which the pivot pin 31 may selectively engage. This is for the purpose of adjusting the distance of the horizontal safety bar 33 below the 75 brake beams. The safety bar is suspended from the rod 30 by means of a chain 34 and a link 35, the latter having pivotal engagement, as at 36, near one end of the safety bar 33. The link 35 is preferably 80 of square or rectangular cross section and is guided in a brace 37 for the purpose of preventing twisting or displacement of the horizontal safety bar 33.

At 38 is shown a fixed stop under the bottom 85 of the car and adapted to limit the swinging movement of the trigger 23 when the latter is actuated by the rocking of the safety bar 33.

Reference numeral 40 represents a brace 90 for the chain 34 which brace is bolted to the sand bolster 45 of the car so that the safety bar will be properly located with relation to the brake beams.

The operation of the device is as follows: 95 With the safety appliance installed, as indicated in Figures 1 and 6, on a car truck and attached to the air pipe line 11, the safety bar extends lengthways under the truck beyond the front and rear brake beams 100 46 and 47 slightly below the same. In case one or both of the latter should be detached and dropped down it will fall on the safety bar 33 and its weight will press the safety bar downwardly. This action is communicated through the link 35, chain 34 and rod 30 to the long arm 28 of the trigger 23. The latter will then turn against the action of the spring 39, thereby swinging the trigger toe 22 upwardly and lifting the stem 110 17 with the valve 16. This swinging movement of the trigger 23 is limited by the stop

38 so that the spring 39 cannot be compressed more than to a certain extent but sufficiently to permit the lifting of the valve 16. As communication is now open between 5 the main chamber 12 and the relief chamber 13 in the cage 10, the compressed air in the pipe line 11 will escape through the valve seat 15 into the relief chamber 13 and from there to the atmosphere through the vent 10 20. The air brakes will accordingly be applied in the usual manner and the train stopped. The escape of air will continue as long as the safety bar 33 is loaded, that is, to say, until the fallen brake beam is removed. As soon as the weight is taken off 15 the safety bar 33 the spring 39 will press down the trigger toe 22 and lift the safety bar 33 into its normal position. At the same time the valve 16 will drop back into 20 its seat 15 partly actuated by gravity and partly by pressure in the main chamber 12, the lower end of the stem 17 having been released by the toe 22.

Having thus described the invention, what 25 is claimed as new is:

1. A safety appliance for cooperating with the brake beam of an air brake; said appliance comprising a valve cage inserted in the air pipe line, a valve seat in said cage connecting said pipe line with the atmosphere, a valve normally closing said seat, a trigger, a safety bar positioned beneath said brake beam, and suspension means for said safety bar connected with said trigger. 30 35 40 45

2. A safety appliance for cooperating with the brake beam of an air brake; said appliance comprising a valve cage inserted in the air pipe line, a valve seat in said cage connecting said pipe line with the atmosphere, a valve normally closing said seat, a trigger, a safety bar positioned beneath said brake beam, and suspension means for said safety bar connected with said trigger; said means including a spring tending to hold said trigger out of engagement with said valve. 50 55 60 65

3. A safety appliance for cooperating with the brake beam of an air brake; said appliance comprising a valve cage inserted in the air pipe line, a valve seat in said cage connecting said pipe line with the atmosphere, a valve normally closing said seat, a trigger, a safety bar positioned beneath said brake beam, and suspension means for said safety bar connected with said trigger, said trigger being pivoted on said cage and provided with a toe and an arm, said toe being situated in the path of reciprocation of said valve. 70 75 80 85

4. A safety appliance for cooperating with the brake beam of an air brake; said appliance comprising a valve cage inserted in the air pipe line, a valve seat in said cage connecting said pipe line with the atmosphere, a valve normally closing said seat, a 90 95 100 105 110

trigger, a safety bar positioned beneath said brake beam, and suspension means for said safety bar connected with said trigger, said trigger being pivoted on said cage and provided with a toe and an arm, said toe being situated in the path of reciprocation of said valve; said means including a spring tending to hold said toe out of engagement with said valve. 115 120 125

5. A safety appliance for cooperating with the brake beam of an air brake; said appliance comprising a valve cage inserted in the air pipe line, a valve seat in said cage connecting said pipe line with the atmosphere, a valve normally closing said seat, a trigger, a safety bar positioned beneath said brake beam, and suspension means for said safety bar connected with said trigger, said trigger being pivoted on said cage and provided with a toe and an arm, said toe being situated in the path of reciprocation of said valve; said means including a spring tending to hold said toe out of engagement with said valve, and a rod having adjustable, pivotal engagement with said arm of the trigger. 130 135 140 145 150

6. A safety appliance for cooperating with the brake beam of an air brake; said appliance comprising a valve cage inserted in the air pipe line, a valve seat in said cage connecting said pipe line with the atmosphere, a valve normally closing said seat, a trigger, a safety bar positioned beneath said brake beam, and suspension means for said safety bar connected with said trigger, said trigger being pivoted on said cage and provided with a toe and an arm, said toe being situated in the path of reciprocation of said valve; said means including a spring tending to hold said toe out of engagement with said valve, a rod having adjustable, pivotal engagement with said arm of the trigger, a link fulcrumed on said safety bar, and a pliable member connecting said link and said rod. 155 160 165 170 175

7. A safety appliance for cooperating with the brake beam of an air brake; said appliance comprising a valve cage inserted in the air pipe line, a valve seat in said cage connecting said pipe line with the atmosphere, a valve normally closing said seat, a trigger, a safety bar positioned beneath said brake beam, and suspension means for said safety bar connected with said trigger, said trigger being pivoted on said cage and provided with a toe and an arm, said toe being situated in the path of reciprocation of said valve; said means including a spring tending to hold said toe out of engagement with said valve, a rod having adjustable, pivotal engagement with said arm of the trigger, a link fulcrumed on said safety bar, and a pliable member connecting said link and said rod; an abutment on said cage adapted to limit the swinging movement of 180 185 190 195 200

said trigger in one direction, and a stop fixedly arranged to limit the swinging movement of the trigger in the opposite direction.

5 8. A safety appliance for cooperation with the brake beam of an air brake, said appliance including a normally closed valve inserted in the air pipe line, said valve when open serving to connect the air pipe line

with the atmosphere, a valve unseating member, an impact receiving member positioned beneath the brake beam, and suspension means for said impact receiving member operatively connected with the valve unseating member.

15

In testimony whereof I affix my signature.

JOE LIDDELL. [L. S.]
